UNITED STATES PATENT OFFICE.

HERMAN BESSER, OF ALPENA, MICHIGAN.

FUEL ECONOMIZER AND SMOKE-PREVENTION MECHANISM.

Application filed March 15, 1923. Serial No. 625,265.

To all whom it may concern:

Be it known that I, HERMAN BESSER, a resident of the city of Alpena, county of Alpena, and State of Michigan, and a citizen 5 of the United States of America, have invented certain new and useful Improvements in Fuel Economizers and Smoke-Prevention Mechanism, of which the following is a specification.

10 This invention relates to fuel economizers and smoke prevention mechanism, and has especial reference to means for utilizing the maximum number of heat units in the products of combustion, at the same time extracting the unburned carbon content of such 15 products before directing the resulting waste gases to the chimney flue, thus reducing the annoying black smoke ordinarily emitted therefrom, as well as reducing the amount of 20 fuel necessary to satisfy given heating requirements.

The purpose of my invention is to provide 25 mechanism for conveying the combustion products from a fuel-burning element to the usual chimney flue, at the same time enclosing such conveying mechanism whereby heat radiated from the latter, and ordinarily wasted, may be utilized for heating purposes.

30 Another object of my invention is to provide a substantially horizontal smoke conveying drum having a series of spaced baffles therein and secured at their upper edges to the inner surface of the drum but clearing the said surface at their lower edges, thus affording means at the upper part of 35 the smoke channel for collecting thereon surplus carbon content of the combustion products, thus clearing the gases emitted from 40 the chimney, though not preventing necessary current of gases therethrough to provide essential draft for the fuel burning element.

A further object of my invention is the 45 provision of a telescoping drum mechanism having an appreciable space between the drums, the inner drum conveying combustion products therethrough, while the intervening space conveys heat radiated from the 50 inner drum, and ordinarily wasted, therethrough and directs it to points to be heated.

It is a still further object of my invention to provide a smoke-conveying drum having baffles for collecting soot or other carbon

thereon, and also having collection trays for 55 receiving the ash product of a combustion of the matter collected on such baffles.

The above-mentioned as well as other objects of my invention I attain by the new construction, combination and arrangement 60 of parts described in this specification, defined in the appended claims, and illustrated in the accompanying drawings, in which—

Figure 1 is a side elevation of my structure shown in relation to a suitable furnace 65 unit;

Figure 2 is a central, longitudinal, vertical section of my heat economizing drum structure, and

Figure 3 is a transverse section of the 70 drum structure taken on the line 3—3 of Fig. 2, looking in the direction of the arrows.

Referring now to the drawings in detail, in which corresponding parts are represented by similar reference characters 75 throughout the several views, an outer drum A is shown suitably supported on vertical standards B, and is connected by suitable pipes with the furnace C, which may be of a standard make, adapted to burn any desirable fuel, such as coal, gas, oil or wood; and adapted to heat building space in the ordinary manner, as by air, steam or hot water currents.

Within the drum A is another and smaller 85 drum 10 of substantially equal length, but positioned therein and preferably eccentrically, being nearly tangentially arranged at the lower sides, leaving an intermediate air space 11 between the drums which is 90 sealed except at the ends as described later. These drums are otherwise perfect cylinders, but have at their lower edges downwardly extending flanges 12 and 13, as shown clearly in Fig. 3. The flanges 12 of 95 the inner drum protrude down through the opening between the outwardly-bent edges 13 of the outer drum, the latter being suitably fastened to the former, as by rivets 14.

The ends 15 and 16 of the drum structure 100 have suitable openings therethrough and are appropriately secured at their edges to the outer walls of the drum A, as by rivets 17, while the edges of the inner drum 10 are suitably secured by similar flange means 18 105 to the said ends, except at the lower trough-like parts formed by the flanges 12 and 13. The usual smoke pipe 19 connects the drum

10 with the furnace chamber, while from this drum a similar smoke flue 20 connects with a wall chimney.

It is to be understood that no smoke is ever permitted to enter the intermediate space 11 which is heated normally by radiation only from the smoke carrying drum 10 which it envelops. An air pipe 21 is, however, provided to pour heated air from 10 the outer air chamber or hood of a furnace if such is used, into the aperture 22 in the end plate 16, as in starting a fire at first, but normally it is closed by a suitable damper 23, other means being utilized to 15 serve the heat in the space 11. In any case, pipes 24 lead from the outer wall A of the large drum and are directed to the space or chambers to be heated. If desired, they may be used to heat certain rooms of a building as by being directed to the usual registers; it is however my purpose to heat intramural spaces of building walls and to accomplish this by forcing heated gases therethrough. My structure is well adapted 25 for the latter purpose in which case, the pipes 24 will be directed to suitable openings in the walls of the building; and where the wall space is divided as is contemplated, into a plurality of channels, one of these 30 pipes may be led into as many of these channels as may be desired.

It is not desired however to limit the present application to the details for wall heating; and further details are not disclosed, since that feature involves another invention of mine, and is not claimed in this application. In any case however, the drum end 16 is provided with openings 25 therein leading to the space 11, there being 40 provided pivoted closures 26 to cover or partly cover said openings as may be desired.

Suspended from the roof of the inner drum 10 is a series of spaced baffles or discs 45 27 secured rather loosely to the inner surface of the drum 10 by means of certain spaced ears 28 which may be riveted to the drum wall. These baffles may be provided in larger or smaller numbers, usually spaced 50 a foot or less apart, the exact distance being not considered of relative importance, and may clear the floor of the drum to provide an unobstructed passage 29 through the whole length of the structure from the furnace pipe to the chimney flue. It is to be 55 noted though that this channel is at the lowest point in the drum, and that the hot gases from the fire pot will rise to the highest points attainable, which in this instance will be the spaces between the baffles. Only the draft produced by relative 60 weights of gases in the furnace and chimney will force a current through this drum, the action obviously giving rise to whirling eddies of gases between these baffle plates

finally being caught in the main current in the channel 29 and thence passing into the wall chimney.

In this travel of the smoke through the drum 10, the superabundant carbon from 70 the smoke clings to the said baffles 27 as a soot, leaving a cleaner net result of the products of combustion to leave the drum at 20. This process results not only in heating the outer space 11 by radiation from the flue 75 10, thus saving heat units from the current received from the furnace, that would be otherwise wasted, but also serves as a smoke prevention means to prevent the issuance of black smoke from the chimney of the 80 building.

The flanges 12 with the bottom closure therefor form a trough-like structure which serves as a receiving means into which any products from above may fall and be emptied when convenient. To this end, certain sections of the trough are provided with hinged lids or trays 30 pivoted at 31 to the said flanges 12, there being provided suitable latches 32 to secure them closed normally. Between these pivoted sections, of which there may be any desired number—usually a plurality, at least, are fixed sections 33 integral with one or both of the flanges 12. The latter fixed sections may be 95 readily cleaned from the open sections, and the latter emptied of their contents into a suitable receptacle.

The furnace has fresh air fed into it at 34 from a suitable source, the latter arrangement forming no part of this invention and therefore not described in greater detail.

Operation:—The use of this device requires no radical change in the arrangement of the furnace or smoke chimney; in fact, 100 the usual smoke pipe leading from the former to the latter may often be discarded and my drum structure substituted therefor, the short pipe section 19 being connected with the smoke opening in the drum 110 head 16, and the other end—15 connected with the chimney by the section 20. The pipe section 21 is intended to be led from the air chamber in the furnace hood to the entrance to the space 11, between the drums, 115 and being used or not, as may be desired. Normally, currents entering at the open apertures 25 from the air surrounding the drums, and passing through said space and thence out through the pipes 24 to the space 120 to be heated will be found sufficient to adequately utilize the heat radiating from the inner drum 10; but when it may be advantageous for any reason to make further use of the mechanism described to direct warm 125 air out through the pipes 24 and thence to a particular space with which they may be connected, such as the intramural space in the building walls, and in greater volume than the radiation from such inner drum 130

may afford at a given time, then the damper 23 may be opened to permit hot air to rush directly from the furnace hood through the pipe 21, and through space 11 and out the pipes 24, at the same time carrying with it whatever heated air has already accumulated in said space by radiation. In any case, however used, my new mechanism provides for two separate functions; one, that 10 of making use of every possible heat unit in the smoke leaving the furnace, thus resulting in economy of fuel, and a second that of relieving the smoke of the solid carbons before the purified and filtered gases 15 are delivered into the chimney flue, thus aiding greatly in smoke prevention.

As the soot made up of various carbons is deposited on the inner surface of the drum 10 as well as on the baffles themselves, it is 20 necessary to clean such surfaces at suitable intervals. This is done by firing the soot from the furnace end of the drum, usually by temporarily increasing the draft in the furnace thus causing flames to reach into 25 the drum 10 and burn out substantially all the soot clinging to the baffles or other surface within it, at the same time raising greatly the temperature of the space 11 which is a further saving in fuel. The ultimate 30 result of this special combustion is an ash which is referred to above as falling into the trough formed by the flanges 12. The soot collected in said drum 10 may be burned daily if desired or at convenient intervals of greater length, but the ashes resulting from such burning need not be emptied from the said trough oftener than once or twice a year, usually, as it will be evident that the volume of these deposits 35 will be quite small. The unlatching of the catch 32 permits the swinging of the trays 30 downward on their pivots 31 for cleaning and at the same time affording opportunity for cleaning the intervening space 33.

It is to be particularly noted that the drums may be built to fit the conditions existent where they are to be used; that their length may be varied within wide limits depending upon the space between the furnace and wall chimney, upon the size of the furnace needed for a given building, and somewhat upon the character of fuel used; that their peripheral size varies with the size of smoke pipe leading from the furnace, and that the size of baffles depends upon the cross section of the drums. I do not therefore confine myself to the particular relative size of parts here shown nor to the exact relative arrangement of parts here 50 described. The number of baffles found to be most advantageous in a given structure has been rather under estimated in the disclosure here made—in the interest of clearness of outline and more certain understanding of detail. In actual use the number will 55 be multiplied over that illustrated in the drawings of this case. It is my purpose to use sufficient of said baffles to conserve the heat in smoke gases and to receive all solids therefrom in the passage through the drum, 70 the baffles being placed sufficiently close together to accomplish this function before the resulting residue is emitted at 20.

While my double tube mechanism has hereinbefore been referred to as comprising 75 drums, this term is meant to be generically not as limited to cylindrical drums, although in many cases the latter form will be found to be convenient and desirable. It is particularly emphasized, however, that many 80 other shapes may be used in other cases, such as polygonal hollow tubular bodies, the main feature, when the two tubes are used, being that one of them shall enclose the other, so that combustion products may be passed 85 through the inner tube, and air to be heated passed through the intervening space. And this condition will be found to be present whatever the particular cross section of the tubular bodies may be. 90

Further, while I have shown a pipe leading from the air chamber of the furnace C to the space 11, in some cases this need not be used, the apertures 25 being relied upon to admit sufficient air into this end of the 95 structure. Also, the pipes 24 may in some cases be more desired if leading from the end 15 rather than from the outer wall of A, it only being essential that they lead from space 11. 100

It will further be understood that many other changes may suggest themselves in given situations without in any way avoiding the general idea of my invention, and while I have described my invention as taking a particular form, it will be understood that I do not limit myself to the precise construction set forth, but consider myself at liberty to make such changes and alterations as fairly come within the scope 105 of the appended claims. 110

Having thus described my invention, what I claim as new and desire to secure by Letters Patent is:—

1. The combination of a pair of drums, 115 one positioned eccentrically within the other and having common end closures, pipes communicating with the interior of the inner drum through said closures, means in one of said end closures for permitting entrance 120 of air into the space between the drums, and pipe means leading from said space near the opposite end adapted to convey heated air therefrom to a distant point. 125
2. The combination of a composite tubular device, comprising a smaller tube internally tangent within another, a hot air furnace, pipe connections from the fire pot of the furnace to the interior of the inner tube, pipe connections between the space between 130

the tube and the air chamber of the furnace and with a space to be heated, and an ash collection device secured externally to said tubes and communicating with the interior tube at the point of tangency.

3. The combination of a smoke drum for conveying gases from a fuel burner to a chimney, a heating drum inclosing the first said drum with a space therebetween, the inner drum formed of a quadrilateral sheet curved until its edges nearly meet and which edges are bent outwardly in parallelism and project through the peripheral wall of the outer drum, thus affording a means of communication between the interior of the inner drum and space outside the heating drum, common end closures for said drums and means for passing a current through the space between the drums.

4. The combination of a pair of drums, one positioned eccentrically within the other and having common end closures, spaced baffle plates within and attached by a portion of their edges to the smaller drum, other edge portions being spaced from the surface of the drum, pipes entering one of the ends of the smaller drum and communicating with its interior, means for carrying heated air from an adjacent furnace to the intermediate space between the drums at one end, and pipe means leading from said space near the opposite end adapted to convey heated air from said space to a point to be heated.

5. A heat radiating mechanism, comprising an elongated, hollow structure including therein an enclosing space sealed from communication with the space within it and having closed ends, one of said ends having apertures therein and movable covers for closing or opening such apertures at will, pipe means connecting with said apertured end for permitting communication between said space and the air chamber of a heater, pipe means connecting with the opposite end of the enclosure for conveying air current to a distant point to be heated, and means for directing smoke from a heater into one end of the inner space in such structure and out the opposite end thereof to a suitable chimney flue.

6. In combination, elongated, telescopically-arranged, spaced tubes with common end closures therefor, a series of spaced baffles within the inner tube engaging by a portion of their edges the curved inner surface of said tube, but the remainder of their peripheral edges clearing the said inner surface, thereby forming an open channel from end to end, means connected with said end closures for passing combustion products through said inner tube, and means for passing an air current longitudinally of the space between said tubes.

7. The combination of a smoke tube, an

air tube enclosing the first said tube with a space therebetween, common end closures for both said tubes, both of said tubes being slotted longitudinally and the edges of the inner tube bent outwardly and extending 70 radially through the slot in the outer tube, refuse receiving means detachably connected with said extensions, whereby said receiving means communicates with the interior of the inner tube but not with said space, connections affording heated gas currents through the inner tube, and other connections affording air currents through said intermediate space.

8. A fuel economizing and smoke prevention device, comprising a pair of substantially horizontal drums of equal length and unequal diameter, the smaller drum being enclosed by and arranged substantially tangent internally to the larger, and the two 85 having common end closures, their common tangency being at their lower surface and each having a longitudinal slot, longitudinal flanges from the inner drum on either side of said slot projecting downwardly through the slot of the larger drum and affording a horizontal trough, means for closing said trough and thereby affording collecting means for receiving any ash or other particles falling thereto, pipes entering the 90 ends of the smaller drum and communicating with its interior, one of said end closures having apertures therethrough leading to the space between the drums, some of said apertures communicating with the air outside the drums, and another with the heat chamber of a heating element, means for closing or opening any or all of said apertures, and means adjacent the opposite end 95 of the drums for affording communication between said intermediate space and a space to be heated.

9. In a fuel economizing and smoke prevention mechanism, a cylindrical drum having closures at its ends, pipes connected with such closures, and baffle plates spaced from each other and having means for attachment at portions of their edges with the inner surface of the drum, other of their edge portions being spaced from the 110 drum surface and in alignment to form a clear unobstructed channel the length of the drum.

10. In a fuel economizing and smoke prevention mechanism, a cylindrical drum having closures at its ends, pipes connected with such closures, means within said drum for partially obstructing the passage of combustion products therethrough, but said means being spaced from the curved lower surface of the drum to form a clear unobstructed channel therethrough, and means connected with the periphery of the drum adjacent said channel for collecting any 115 ash or other particles falling thereto.

11. A fuel economizing and smoke prevention mechanism, including therein an elongated, hollow smoke conveyor having closures at its ends, and adapted to be mounted approximately horizontally for conveying combustion products from a fuel burner to a chimney flue, pipes connected with such closures and means on the lower side of said conveyor for collecting any ash or other particles falling thereinto, including spaced, pivoted trays adapted to swing downwardly on their fulcrums for emptying them. 50
12. In a fuel economizing and smoke prevention mechanism, an elongated, hollow smoke conveyor having closures at its ends, and adapted to be mounted substantially horizontally for conveying combustion products from a fuel burner to a chimney flue, and baffle plates spaced from each other and having means for attachment at portions of their edges with the inner surface of said conveyor, other of said edges being spaced in alinement from the conveyor surface to form a clear unobstructed channel therethrough. 55
13. In a fuel economizing and smoke prevention mechanism, a cylindrical drum having closures at its ends, pipes connected with such closures, spaced, baffle plates having means for attachment at portions of their edges with the inner surface of the drum, other portion of their edges being spaced from the drum surface to form a clear unobstructed channel therethrough, and means connected with the periphery of the drum adjacent said channel for collecting any ash or other particles falling thereinto. 60
14. In a fuel economizing and smoke prevention mechanism, a cylindrical drum adapted to convey combustion products substantially horizontally from a fuel burner to a chimney flue, closures at its ends and pipes connected therewith, spaced, baffle plates having means for attachment at portions of their edges with the inner surface 65
- of the drum, other portion of the baffle edges being spaced from the drum surface to form a clear, unobstructed channel the length of the drum, and means connected with the periphery of the drum adjacent said channel for collecting any ash or other particles falling thereinto, said collecting means including swinging tray parts for emptying the same. 70
15. A fuel economizer and smoke prevention mechanism including therein an elongated smoke conveyor having closures at its ends and adapted to be mounted approximately horizontally for conveying combustion products from a fuel burner to a chimney flue, pipes connected with such closures, and means on the lower side of said conveyor for receiving any ash or other particles falling thereinto, including trays adapted for movement relative to the conveyor for emptying them. 75
16. A tubular smoke conveyor formed from a quadrilateral sheet curved until its edges nearly meet and which edges are bent outwardly in parallelism, in combination with refuse receiving means including trays mounted upon said parallel edges and movable relative therewith for emptying them. 80
17. A smoke conveyor comprising a longitudinally slotted tubular device whose longitudinal edges are bent outwardly in parallelism, in combination with receiving means detachably connected with said parallel edges for closing the opening therebetween. 85
18. A smoke conveyor comprising a longitudinally slotted cylinder whose longitudinal edges are bent outwardly in parallelism, in combination with movable means for opening and closing said slot. 85
